[57] CLAIM

The ornamental design for a container for baby formulae, as shown and described.

DESCRIPTION

FIG. 1 is a perspective view of a container for baby formulae, showing my new design;

FIG. 2 is a top view thereof;

FIG. 3 is a front elevational view thereof;

FIG. 4 is a left side elevational view thereof, the right side elevational view being identical;

FIG. 5 is a rear elevational view thereof;

FIG. 6 is a bottom view thereof;

FIG. 7 is a perspective view of a second embodiment of the container for baby formulae, showing my new design;

FIG. 8 is a top view thereof;

FIG. 9 is a front elevational view thereof;

FIG. 10 is a left side elevational view thereof, the right side elevational view being identical;

FIG. 11 is a rear elevational view thereof; and,

FIG. 12 is a bottom view thereof.
